UNITED STATES PATENT OFFICE.

WILLIAM H. MUSSEY, OF HOLLIS, NEW YORK.

TRAP-DOOR-OPERATING MECHANISM.

1,269,557.

Specification of Letters Patent.

Patented June 11, 1918.

Application filed March 17, 1917. Serial No. 155,520.

To all whom it may concern:

Be it known that I, WILLIAM H. MUSSEY, a citizen of the United States, and a resident of Hollis, in the county of Queens, State of New York, have invented certain new and useful Improvements in Trap-Door-Operating Mechanism; and I do hereby declare the following to be a full, clear, and exact description of the invention, such as will enable others skilled in the art to which it appertains to make and use the same.

This invention is directed to the provision of an improved form of spring-actuated hinge for use in supporting the trap-door of a vestibule railway passenger car for elevated or grade level platforms. Such a trap-door is mounted by means of hinges upon the end wall of the car and is normally disposed horizontally over the steps in continuation of the floor of the car so as to complete the floor of the vestibule and thus permit passengers to walk directly from the car to the elevated or grade level platform. When desired the door may be turned on its hinges to an upright or vertical position close to the end wall of the car to permit an unobstructed use of the steps. Such trap-doors are usually held in the closed or horizontal position by a latch and are provided with springs to lift them automatically to open position when the latch is released.

In my earlier Patent No. 1,202,566 of October 24, 1916, there is disclosed a novel form of hinge for such trap-door involving the use of a hollow casing for the spring, with the casing comprising two sections so connected that one of such sections, attached to the trap-door, is rotatable relative to the other section, attached to the car end. The spring thus inclosed is arranged to be compressed, on lowering the door to the horizontal position, by means of a pair of co-acting members one fixed in one of the two casing sections and the other guided for axial movement in the other casing section. As a result of this construction, the axially movable member compresses the spring during a lowering of the trap-door; so that, upon subsequently releasing the latch which holds the trap-door in its horizontal position, the spring expands, and by returning the axially movable member to its normal position causes a rotative movement of the

other member and its casing section and thereby swings the attached trap-door up to its open or vertical position. It is apparent that on the upward movement of the trap-door the center of gravity thereof approaches closer and closer the vertical plane of the axis of movement; less and less weight of the door, therefore, resisting the lifting effect of the spring as the door swings up more and more from its horizontal position, until, with the door in vertical position, the entire weight is supported on the hinge. Moreover, at the instant the door is started on its upward swing, the single spring must overcome the inertia of the door and the starting friction of the various moving parts. It is this single spring which must accommodate itself to the rapidly changing load in the different positions of the door, and in such a way that the door may be suitably stopped when it reaches its vertical position, without slamming heavily against the car end. According to the construction of this previous patent, the co-acting members must be of such design that by their co-action during the expansion of the single spring employed, this spring exerts a very powerful action at the instant the latch is released and a rapidly diminishing action as the door is turned upward.

The main object of the present invention is to provide certain improvements in this previous construction. One of these improvements involves the use of a plurality of springs arranged to operate in tandem and so designed and co-acting with the other elements that the counter-balancing effect of the entire structure follows a curve practically coincident with the curve of the resistance of the trap-door to elevation. This curve, it is clear, will be a sine curve, since as the door is moved upward, the load varies inversely as the sine of the angle between any two successive inclined positions of the door and its horizontal position.

Among other improvements, the present invention provides a combined anti-friction rotative and thrust bearing, to coöperate with the spring system peculiar to the present invention; this bearing also serving incidentally to connect and lock the two casings together, so as to make of them and their contents a counter-balancing hinge which is a

85

100

105

self-contained unit, and to thus obviate any necessity for depending upon the auxiliary hinge of the trap-door as the means for preventing a separation of the two casing sections.

The invention will be clearly understood from the following description, when taken in connection with the accompanying drawings, of which Figure 1 is a diagrammatic view in elevation of a portion of the end of a railway passenger car; Fig. 2 shows in end elevation and on an enlarged scale the counter-balancing hinge shown in end elevation in Fig. 1; Fig. 3 is a section on the line 3—3 of Fig. 2, the auxiliary hinge being shown to the left of Fig. 3; Fig. 4 is a section on the line 4—4 of Fig. 3; Fig. 5 is a section on the line 5—5 of Fig. 3; Fig. 6 is a section on the line 6—6 of Fig. 8; Fig. 7 is an end elevation of the left-hand casing section shown in Fig. 6, and of the member therein; Fig. 8 is a section on the line 8—8 of Fig. 6; Fig. 9 is a section on the line 9—9 of Fig. 3; and Figs. 10, 11, 12 and 13 are detail views, Figs. 11 and 12 showing in perspective the co-acting members carried by the casing sections, and Figs. 10 and 13 being respectively end elevations of the members of Figs. 11 and 12.

Referring to these drawings, Fig. 1 shows a portion of the end of the car body 15 and the trap-door 17, the latter being shown in its closed position.

As shown best in Fig. 3, the counter-balancing hinge comprises a self-contained unit including a casing section 18, affixed to the under side of the door 17, and a complementary casing section 19 affixed to the car end. In order that a single means may interlock the two sections into a single casing for the counter-balancing unit, and at the same time furnish a combined anti-friction rotative and thrust bearing between the two casing sections, an annular groove is formed exteriorly of the section 18 and a similar groove is formed interiorly of the section 19, these two grooves forming the ball-race for a ball-bearing 20 when the ends of the two sections are fitted one within another as shown in Figs. 3 and 6.

Within the hollow casing are two co-acting members 21 and 22. The member 21 is secured within the casing section 18 so as to rotate with that section when the door 17 is swung up or down. The member 22, while axially movable within its casing section 19, is restrained against rotation thereto by the polygonal cross-sections of these two parts interfitting as shown in Fig. 5. Fig. 12 shows clearly the portion 22^a of the member 22 as being of this polygonal cross-section. Fig. 3 shows this axially movable member 22 at its extreme inner position in its casing section 19, thus to compress a plurality of springs 23, 24, 25, 26

and 27. It will be observed that the springs 23 and 24 when compressed are almost completely housed within a cylindrical recess formed in the portion 22^a of the member 22, and the springs 26 and 27 when compressed are similarly housed within a cylindrical recess formed in a plug 29 and axially alined with the similar recess formed in member 22; this plug 29 being threaded in the outer open end of the casing section 19. The intermediate spring 25 is separated from the two terminal groups of springs thus housed, by means of piston disks 30.

While the springs are expanding or being compressed, these piston disks of course move axially of the casing section 19. These disks, however, are always maintained concentric with the springs, by means of the ribs 19^a shown in Figs. 3, 4 and 5, and the four straight, inclined walls defining the polygonal cross-section of the casing section 19. This polygonal subdivision of section 19, lies between the points 19^x and 19^y of Fig. 3. As indicated clearly in Fig. 5, the piston disk to the left of Fig. 3, may slip smoothly from the guidance of ribs 19^a to that of these four inclined walls, and vice versa; the other piston disk always keeping to the four ribs. In this connection it will be noted that keys and keyways are entirely dispensed within the casing section 19; which also is true of casing section 18.

Plugs or cores 24^a and 27^a may be arranged within each of the inner light springs 24 and 27. As shown in Fig. 3, the core 24^a is just a trifle shorter than the solid height of its spring 24, and the core 27^a is just a trifle shorter than the solid height of its spring 27. These cores may be loose within their springs, but it is preferred to form the core 24^a integral with the member 22 and the core 27^a integral with the end plug 29.

The member 21 is permanently anchored in the casing section 18. The member is inserted into the section so that a square reduced extension carried by the member may be swaged into a square hole 18^a as shown at 21^a in Fig. 3. Before the swaging operation is commenced, the screws 33 are employed as shown in Figs. 3 and 7, to set the member 21 ready for swaging, so that the casing section 18 may be arranged vertically to rest on the feet or lugs 34 to protect the outer end face of the member 21 against any chance of marring or burring. It will be understood, of course, that with helical ribs fitting within helical slots with some degree of snugness, any marring or burring of the outer end face of the member 21 will seriously interfere with further assembly of the device. The provision of the conical recess 21^b in the square extension 21^a permits the latter to be swaged in place by blows so di-

rected that the screws 33 will not be subjected to impracticable shearing strains.

In joining the two casing sections, the co-acting members 21 and 22 should be first interengaged, and then the section 18 telescoped within the section 19 to permit the ball-bearing 20 to be formed. Before the casing sections may be thus telescoped, the section 18 must be arranged relative to the section 19 as indicated in broken lines in Fig. 8, that is, the lugs 34 of section 18 must lie opposite the gaps between the two transverse ribs 37 formed inside section 19. Thereupon the lugs are passed through the gaps so as to bring the internal annular groove on the section 19 opposite the external annular groove on the section 18 to form the ball-race for the ball-bearing 20. A proper number of balls may then be deposited in the ball-race by way of a tapped hole for the screw 38, and the parts finally locked together by inserting such screw.

The hinge thus constructed and assembled is secured to the trap-door 17 near the outer edge of the latter. The trap-door near its inner edge, as shown in Fig. 3, is provided with an auxiliary hinge comprising a pintle 39 on the end of a pintle bracket 40 secured to the under side of the trap-door, the pintle turning in a bearing piece 41 riveted to the riser 42 of the top car step.

While the door is being lowered to horizontal position, the member 22 is caused to gradually advance to the right toward the location shown in Fig. 3. At the completion of this movement of the member 22 all the springs are compressed to the predetermined limit, which is reached just as the door snaps into engagement with the usual latch (not shown) for holding the door in its horizontal position. The springs 26 and 27 are together weaker than the combined strength of the springs 23 and 24, which latter are together weaker than the spring 25. Thus, as the door is lowered more and more toward its horizontal position, the resistance to compression of the counter-balancing spring system increases more and more. But as the door is lowered more and more, its center of gravity shifts farther and farther away from the vertical plane of its axis. As a result, the resistance of the door to manual lowering is actually inconsiderable and almost unnoticed. On the other hand, upon releasing the latch which holds the door in its horizontal position, the springs operate as follows: first, a powerful initial upward shove is given, sufficient to overcome the inertia and starting friction of the horizontally arranged door, and to impart enough momentum thereto to carry the door well on its way toward the vertical position; and then the acceleration drops so as to gradually reduce the momentum in correspondence with the diminishing load. The door

is thus given an even movement throughout its whole upswing, although subjected to a powerful shove at the beginning of its movement and finally coming to rest in its vertical position very gently and without any suggestion of a slam. Being arranged in tandem, the springs are all compressed to the predetermined maximum at the same instant, that is, when the door reaches its horizontal position. Preferably, all of the springs are compressed solid when the door is thus lowered.

Should one of the springs break, the door will nevertheless tend to keep its vertical position, or at least will be prevented from falling freely from such position. Also, a broken spring will not jam the counterbalancing hinge so that the door may not be raised to the vertical. Of course no two springs separated by a piston disk 30 may ever become enmeshed to jam the counterbalancing hinge; and the cores 24^a and 27^a prevent the springs 24 and 27 when broken from becoming enmeshed with the springs 23 and 26 with which they are grouped.

These cores 24^a and 27^a act also as stops or spacers to absorb the slight shock which accompanies compression of the springs to the predetermined maximum at the instant when the door reaches its lowered position, and the cores thereby serve to relieve the members 21 and 22 from any undesirable jars and strains to which they might otherwise be subjected.

The ball-bearing 20 serves at once as an interlock, anti-friction journal, and thrust bearing. It interlocks the two casing sections together to make the counter-balancing hinge a self-contained unit at all times. As a result, the counter-balancing hinge need not be assembled while being attached to the car end and trap-door and after the pintle 39 has been inserted in its bearing piece 41; and the hinge may be removed at any time without first having to take the same apart. The ball-bearing 20 serves also as an anti-friction journal to facilitate the orderly compression and expansion of the springs as predetermined, and to permit the members 21 and 22 to interfit with a less degree of snugness than would otherwise be required. The ball-bearing 20 serves further as a thrust bearing, and thereby avoids putting any thrust pressure on the trap-door to be taken up by the bearing piece 41 of the auxiliary hinge. To this end the lugs 34 of the member 18 coöperate with the ribs 37 of the member 19 to give the thrust bearing the requisite strength, and at the same time to afford a simple and convenient means for permitting the member 18 to be telescoped within the member 19 before they are interlocked. In this connection, it is pointed out that these lugs 34 are the same lugs which were useful in permitting the square exten-

sion 21^a to be swaged into place without injuring the member 21.

I claim:

1. A counter-balancing means for a trap-door hinged to swing on a horizontal axis eccentrically disposed relative to the center of gravity of the door, comprising, in combination, a hinge member secured to a fixed portion of the car, a complementary hinge member secured to the door, and a plurality of springs operatively associated with the two members, the springs being so relatively tensioned that when the door is released in its horizontal position first both and then one only of said springs will act on the door to lift it toward its horizontal position.

2. In a counter-balancing means for a trap-door of the kind described, in combination, a hinge member secured to a fixed portion of the car, a complementary hinge member secured to the door, a part fixedly carried by one of the members, a part movably carried by the other member and adapted to move relatively to the first-mentioned member as the door is lowered toward vertical position, and a plurality of springs of different strengths arranged in tandem to be compressed during said relative movement between said two parts.

3. In a counter-balancing means for a trap-door hinged to swing on a horizontal axis eccentrically disposed relative to the center of gravity of the door, in combination, a hinge member secured to a fixed portion of the car, a complementary hinge member secured to the door, spring-compressing means carried partially by one of said members and partially by the other, and spring means compressed by the spring-compressing means as the door is swung from its vertical to its horizontal position, the spring means being so designed that as the door is lowered and its center of gravity moves farther and farther away from the vertical plane passing through the door's axis the resistance to compression of the spring means correspondingly increases.

4. In a counter-balancing means for a trap-door hinged to swing on a horizontal axis eccentrically disposed relative to the center of gravity of the door, in combination, a hinge member secured to a fixed portion of the car, a complementary hinge member secured to the door, spring-compressing means carried partially by one of said members and partially by the other, a plurality of springs of different strengths to be compressed by the spring-compressing means when the door is in its horizontal position, the parts being so designed that when the door is released from its horizontal position the various springs act to first move the door upward with a force sufficient to overcome its inertia and starting friction and then continue the movement while diminishing

the force in correspondence with the diminishing load as the door's center of gravity approaches closer and closer the vertical plane passing through its axis.

5. In a counter-balancing means for a trap-door of the kind described, the combination with the two-section casing and the co-acting relatively rotatable members arranged therein so that one of these members establishes a spring recess within one of the sections the length of which recess is to be shortened by the movement of one of said members when the door is being lowered to horizontal position, of a spring system confined in the recess and comprising a plurality of springs of different strengths which are simultaneously variously compressed as the length of the recess is shortened.

6. A counter-balancing means for a trap-door of the kind described, comprising, in combination, a hinge mounting therefor, and a spring means associated with such mounting for being compressed when the door is lowered to its horizontal position and for moving the door from its horizontal to its vertical position, the hinge mounting including two relatively movable hinge members one of which partially telescopes within the other, and an interlocking means for the two sections including a ball-bearing the ball-race of which is partially carried by one of the hinge members and partially by the other.

7. A counter-balancing means for a trap-door of the kind described, comprising, in combination, a hinge mounting therefor, and a spring means associated with such mounting for being compressed when the door is lowered to its horizontal position and for moving the door from its horizontal to its vertical position, the hinge mounting including two relatively movable hinge members one of which partially telescopes within the other, and an interlocking means for the two sections including a ball-bearing the ball-race of which is partially carried by one of the hinge members and partially by the other, one of the members providing a recess for confining the spring means and the other member having associated therewith and operated thereby a plunger for compressing the spring means when the door is lowered to horizontal position, whereby the ball-bearing interlock acts also as a combined anti-friction rotative and thrust-bearing between the two hinge members.

8. In a trap-door of the kind described, a hinge having a tubular part, a complementary hinge member, a ball-bearing including an annular ball race for operatively connecting the two hinge members, and a counter-balancing means operating within said tubular part.

9. In a counter-balancing means for a trap-door of the kind described, the combi-

nation with the two-section casing and the co-acting relatively rotatable members arranged therein so that one of these members establishes a spring recess within one of the 5 sections the length of which recess is to be shortened by the movement of one of said members when the door is being lowered to horizontal position, of a spring system confined in the recess and comprising a plurality of helical springs of different strengths 10

arranged in line to be simultaneously compressed as the length of the recess is shortened, a plurality of spacer disks for the springs, and a plurality of spacer cores sleeved by the springs, each spacer core being 15 approximately as long as the solid height of the spring which sleeves it.

In testimony whereof I affix my signature.

WILLIAM H. MUSSEY.
